Fig. 5

Fig. 7

A rectangular frame with several numbered components. The top edge has a label '13' at each end. The left edge has a label '13' at the top, '6' in the middle, and '11' at the bottom. The right edge has a label '13' at the top, '6' in the middle, and '12' at the bottom. The bottom edge has a label '13' at each end. Inside the frame, there are two small rectangular components labeled '6' and '10'. The number '15' is positioned in the center of the frame. The number '3' is located in the top-left corner and the bottom-right corner.

UNITED STATES PATENT OFFICE.

KINNEY I. MILLER, OF LANCASTER, MISSOURI.

REINFORCED AND VENTILATED SHIPPING BOX.

Application filed May 6, 1927. Serial No. 189,226.

The present invention relates to shipping boxes as constructed of strawboard, paste board or any other suitably flexible material, and more particularly relates to that form 5 of such boxes wherein the structure is reinforced or strengthened by means of integrally formed hollow ribs or bosses extended across the material of the structure. These integrally formed ribs are generally V-shaped 10 in cross section, and are formed up by crimping, folding, flexing, channeling or corrugating the stock of which the box is made.

Regardless of the particular cross sectional form of hollow rib or boss employed, 15 the prime object of this present invention is to provide a simple, efficient and practical means for preventing the spreading, flattening or collapsing of such ribs under pressure, as when the boxes are stacked up in 20 tiers.

Another object is to provide a reenforced, integral structure for either the lid or body 25 of a shipping box, wherein the reenforcing features or elements will simultaneously serve as spacers for preventing the too close 30 packing of the boxes in rows or tiers, and wherein the said ribs are provided with air openings or cut outs, as means for ventilating the interior of the box.

30 In the drawing

Figure 1 is a plan view of a box lid blank, marked out in accordance with this invention, the solid lines indicating clean cuts through the blank and the dotted lines indicating the lines of flexure for forming the 35 reenforcing ribs and tie tongues directly upon the top of the lid;

Figure 2 is a plan view of a lid after the reenforcing ribs are formed, the side flanges 40 turned, and the free ends of the tie tongues extended beneath the opposite margin of the opening and there fastened to serve as a tie;

Figure 3 is a transverse, sectional view of the completed lid, on the line 3—3 of Figure 2;

Figure 4 is a plan view of a section of a modified form of lid blank, wherein the reenforcing ribs and tie tongues are marked off at two opposite margins of the lid blank, at 50 the points of flexure of the side flanges, instead of directly at the top of the blank as shown in previous figures;

Figure 5 is a plan view of a lid as formed from the blank shown in Figure 4;

Figure 6 is a transverse, sectional view on the line 6—6 in Figure 5;

Figure 7 is a plan view of the same form of lid as shown in Figure 2, illustrating the use of individual and separate tie tongues or straps in lieu of the integrally formed ones, 60 as rib supporting elements.

In constructing a box lid in accordance with this invention, I provide a blank 1 of strawboard or other suitably flexible material and score thereupon rib flexure lines or 65 grooves 2 at two opposite sides of that central portion of the blank 1 intended to serve as the top surface 15 of the completed lid 18; the said grooves being longitudinally aligned, and adapted to facilitate the forming of the longitudinally and transversely spaced reenforcing, spacing and ventilating ribs 3, as will be later pointed out. I further cut the tie tongue or strap incisions 4 clear through the blank, thereby forming the 70 straps or tie tongues 6 which cut medially across the extended longitudinal axes of the ribs 3 arranged in pairs at each side of the blank 1, as stated, the said tongues breaking the continuity of the said longitudinally 75 aligned rib portions. In addition I cut the rib flange incisions 5, the conventional corner incisions 10, and score the conventional side flange flexure lines or grooves 9, the said rib flange incisions 5 at each side of the blank 80 being cut in alignment upon the score lines 9 running transversely to the score lines 2 at two opposite margins of the blank 1. Thus the tie tongues 6 remain integrally connected with the blank 1 at one portion thereof, while their free ends 7 are adapted to be 85 lapped past the edges or margins 8, formed by cutting out the said tongues, as the ribs 3 are formed up.

The blank 1 thus scored and incised is now 90 ready to be formed into the completed lid 18, and this is accomplished by forming up the ribs 3 to a sort of V-shaped formation, which action causes the ends 7 of the straps or tie tongues 6 to lap past the opposed edges 8 of 95 the medial opening made by the cutting out of the tongues from the blank, and the said ends 7 are then securely fastened to the margins 8 by means of staples 11, or in any desired manner. These tie tongues 6 thus effectively serve to prevent the collapsing or spreading of the ribs 3. The side flanges 12 are finally turned down and the corners 13 are folded and secured in conventional manner. The ribs 3 serve as reenforcing elements 100 and also as spacing elements at the top and sides of the box, and at the same time ventila- 105

tion is afforded to the interior of the box upon which this lid is used, through the apertures 14 formed at the ends of the ribs 3.

- In the modification shown in Figures 4 and 5, the flexure grooves 2 are scored along two opposite margins of the blank, with the central line of each group of three lines at each side coinciding with the conventional flexure lines 9 defining the juncture of the top 10 15 of the lid and the side flanges 12 thereof. Thus in the completed lid the portions 3 are formed directly upon and along the corners 17 formed by the top portion 15 and the side flanges 12. Similarly the tie tongues 6 are 15 20 struck out medially of the portions 3 directly upon the corners 17, and the free ends 7 of these tongues are lapped down upon the side flanges 12 and there secured. This form of structure affords comparatively flat top 20 25 and side surfaces for the completed lid 18 where such a structure may be desirable and also throws the ventilation apertures 14 well over to the sides of the box. The fold lines 2 shown in Fig. 4 are adapted to permit a slight upward thrust of the corner 17 of the box, which will result in a slight spacing of the box from another receptacle, and when this occurs there will be a slight flexing of the outer flange 12.
- 30 The straps or tongues 6 are preferably struck integrally from the blank 1, and with one portion remaining integrally connected therewith, as shown in Figures 1 to 6 inclusive of the drawing; but free, individual straps 6 may be employed if preferred, as shown in Figure 7 of the drawing. In this case the two ends of such strap are secured by staples 11 to the opposite margins of the blank immediately at the opening in the 35 40 blank formed between the ends of two adjacent, axially aligned ribs 3.

Of course, the same form of structure as here described for the lid portion of a box, may be also used for a body portion (not shown) if such use should be found desirable; and box lids or bodies so formed are found to be very strong and light, capable of sustaining considerable weight or of being piled upon one another in tiers. In such 45 50 use the tie tongues 6 prevent the flattening or spreading of the ribs 3, and the ribs themselves also afford ventilation and act as spacers for the boxes, preventing them being packed so closely together as to endanger by smothering the live contents of any such boxes.

It will be seen, therefore, that the essential feature of this invention resides in the structure resulting from the breaking of the 60 continuity of what would otherwise be a continuous, integrally formed, V-shaped rib flexure extending across a surface of the box structure, by medially cutting through the said rib portion of the blank at two spaced points and thereby forming two longitudi-

nally spaced and aligned ribs, and then utilizing the opening thus formed through the blank and between the adjacent ends of the two ribs as a seat or situs for the reception of a tie tongue or strap extended across 70 the opening in the blank and fastened to the margins of the blank at each side of the said opening, after the said ribs are formed up, as means for preventing the spreading or flattening of those ribs under weight or pressure; the said tie tongue or strap being formed preferably integrally with the blank and of the intermediate material of the blank resulting from the said incisions through the said rib portion; while at the 80 same time air-ways are formed leading to the interior of the box through the exposed or severed ends of the said ribs.

The invention also includes the blank, marked and incised ready for forming into 85 the said structure.

In the practicing of this invention, any minor changes or alterations may be employed, as may fall within the scope of the appended claims. 90

I claim:

1. A blank for a box lid or body, the same having portions laid out for flexing and forming two hollow, longitudinally spaced reenforcing ribs and a flat, integrally connected 95 tie tongue extended transversely between the said ribs and constituting the separating element therefor.

2. A blank for a box lid or body, the same having portions laid out for flexing and forming two channeled, longitudinally spaced and aligned reenforcing ribs, the portion of the blank separating the two ribs being laid out 100 for forming a tie tongue.

3. A blank for a box lid or body, the same 105 having portions thereof demarcated and incised, and so adapted for forming a lid or body having V-shaped, longitudinally spaced and aligned reenforcing ribs and tie tongues extended transversely between the ribs. 110

4. A blank for a box lid or body, the same having portions demarcated and incised thereupon adapted for forming flexed, longitudinally spaced and aligned reenforcing ribs and tie tongues between the adjacent aligned 115 ends of the said aligned ribs.

5. A box lid or body having flexed, longitudinally spaced reenforcing ribs, and a tie tongue extended between two of the said ribs and constituting the separating and supporting element therefor. 120

6. A box lid or body having hollow, longitudinally spaced and aligned reenforcing ribs, and a tie tongue extended transversely between two of the said aligned ribs for preventing the collapsing of the ribs under pressure. 125

7. A box lid or body having V-shaped reenforcing ribs spaced apart upon their longitudinal axes, and means formed integrally with 130

- the material of the structure interposed between the ends of adjacent ribs for preventing their collapse under pressure. 35
8. A box lid or body having a number of integrally folded, longitudinally spaced reinforcing ribs, and integrally formed tie tongues interposed between the ends of adjacent ribs and arranged to prevent the collapsing of the ribs. 40
10. 9. A box lid or body having a number of integrally formed, longitudinally spaced and aligned reinforcing rib-flexures, and tie tongues extended transversely between the ends of adjacent aligned rib-flexures, the 45 said tie tongues being integrally connected with the material of the structure at one edge of the flexure line, and having free ends whereby they are secured to the material of the structure at the opposite edge of the flexure line in a manner to prevent the collapsing of the rib flexures. 50
10. In a structure of the kind described, embodying an integrally formed, hollowed reinforcing rib, a tongue integrally formed 55 with the rib and having its integral connection at one side of the gap of the rib, and having a free end extended athwart the gap of the rib and secured thereby to the material of the structure at the opposite side of the gap of the rib, whereby the sides of the rib are connected at the base and prevented from spreading. 60
11. A box structure of flexible material, embodying integrally formed rib flexures 65
- spaced apart endwise, the intervening structural material being cut away on all sides except one and formed into a tie strap extended across the opening and secured at its free end to opposite margin of the material, as a supporting element for the said rib flexures. 70
12. A box structure of flexible material, embodying integrally formed rib flexures spaced apart endwise, the intervening structural material being cut away to form an opening; and a strap suspended at its ends across said opening as a supporting element for the said rib flexures. 75
13. In a box structure of flexible material having rib flexures incorporated therein and spaced apart endwise, the intervening material between the ends of the flexures being cut away and forming an opening; a rib flexure supporting element extended across the opening. 80
14. In a box structure of flexible material having rib folds incorporated therein and spaced apart endwise, the intervening material being cut away on all sides save only one and thereby forming an opening through the material; a tie strap formed of said intervening, cut-away material, the free portion of the said strap being extended across the said opening and fastened to the opposite margin of the material. 85

In testimony whereof I affix my signature.

KINNEY I. MILLER.
